UNITED STATES PATENT OFFICE.

OLE HOLEN, OF WYNDMERE, NORTH DAKOTA.

IGNITING SYSTEM FOR INTERNAL-COMBUSTION ENGINES.

1,258,774.

Specification of Letters Patent. Patented Mar. 12, 1918.

Application filed December 26, 1916. Serial No. 138,935.

To all whom it may concern:

Be it known that I, OLE HOLEN, a citizen of the United States, residing at Wyndmere, in the county of Richland and State 5 of North Dakota, have invented certain new and useful Improvements in Igniting Systems for Internal-Combustion Engines, of which the following is a specification, reference being had to the accompanying drawings.

This invention relates to certain improvements in igniting systems for internal combustion engines and it is an object of the invention to provide a system of this general character including novel and improved means whereby a circuit for a sparkler is closed in a convenient and effective manner.

The invention also has for an object to provide a system of this general character 20 wherein is employed a novel and improved circuit closer comprising a rotatable member operatively connected with a sparkler and a contact member coacting with the rotary member and operatively engaged with a requisite source of energy, and wherein said last named member is capable of adjustment relative to the rotary member in order to effect spark control.

The invention consists in the details of 30 construction and in the combination and arrangement of the several parts of my improved system whereby certain important advantages are attained and the device is rendered simpler, less expensive and otherwise more convenient and advantageous for use, all as will be hereinafter more fully set forth.

The novel features of the invention will 40 hereinafter be definitely claimed.

In order that my invention may be the better understood, I will now proceed to describe the same with reference to the accompanying drawings, wherein—

Figure 1 is a view in top plan of an internal combustion engine illustrating an embodiment of my invention applied thereto;

Fig. 2 is a view partly in section and partly in elevation illustrating certain features of the invention as herein embodied;

Fig. 3 is an enlarged sectional view taken through the contact roller as herein included;

Fig. 4 is a view partly in elevation and partly in section illustrating the rotatable member as herein employed;

Fig. 5 is a view in elevation of the rotat-

Fig. 6 is a fragmentary view in top plan of the conductor plates as herein set forth;

Fig. 7 is a transverse sectional view taken through the rotating element or conductor 60 shaft and illustrating the spring contact operatively engaged with a spark plug; and

Fig. 8 is a view in perspective of the spring contact plate as illustrated in Fig. 7, 65 detached.

As disclosed in the accompanying drawings, M denotes a motor of an internal combustion type herein disclosed as comprising four cylinders and with each of which coacts in a conventional manner the spark 70 plug S disposed through the cylinder head, and overlying said heads is the tubular metallic shaft 1 rotatably supported by the bearing 2 affixed to a certain cylinder head, and one end of the shaft 1 is provided with 75 a solid extension 3 to which is affixed the sprocket wheel 4 adapted to be operatively connected with a movable part of the motor M in order to time the sparks for a purpose which is believed to be clearly apparent 80 to those skilled in the art to which my invention appertains. It will be understood that in lieu of a sprocket wheel 4 suitable gearing may be interposed between the extension 3 and a movable part of the motor. 85 The particular means for rotating the shaft forms no essential part of my invention as herein embodied.

The extension 3 is of a diameter slightly less than the diameter of the tubular shaft 90 1 so that the shoulder 5 is afforded which coacts with an adjacent bearing 6 to prevent endwise play of the tubular shaft 1 in one direction, and keyed or otherwise secured to the extension 3 is a collar 7 coacting with 95 the opposite side of said bearing 6, whereby play with the tubular shaft 1 in an opposite direction is prevented.

The opposite end portion of the tubular shaft 1 has suitably fixed thereto a disk 8 of suitable insulating material and provided with the annular groove 9 in its periphery affording the surfaces 10 in which are embedded at predetermined intervals the segments or contacts 11 and 11^a. One set of contacts 11 are electrically connected through the medium of the conductors *a* with the tubular shaft 1 whereby a ground is effected, while the second set of contacts 11^a are electrically connected through the medium of the conductors *b* with the annular contact rings 12 surrounding the shaft 1 at prede-

terminated points intermediate the length thereof and with which are engaged the spring contacts 14 connected with the spark plugs S. It is to be noted that the extremity of each of the spring contacts 14 bearing upon an annular contact 12 is provided with the depending transversely spaced ears 15 coacting with the opposite sides of the annular contact 12 whereby said spring contact 14 is held against displacement relative to the contact 12.

The conductors *a* and *b* are disposed within the tubular shaft 1, which, after the conductors *a* and *b* have been properly connected, is filled with wax or the like in order to maintain the portions of the conductors *a* and *b* within the shaft 1 in substantially a fixed position. It is also to be noted that the annular contacts or rings 12 are insulated from the shaft 1 through the medium of the annular fiber rings 16 surrounding the shaft 1 and interposed between said shaft and the inner walls of the annular contact members or rings 12.

25 The contacts 11 are the low tension contacts while the contacts 11^a are the high tension contacts, and coacting with said contacts 11 and 11^a are the conductor plates 17 carried by the opposite sides of the insulated arm 18, said plates 17 having rotatably supported between their contacting ends the roller 19 of insulated material and provided at its periphery with the transversely disposed annular plates 20 of conductive material which are adapted to contact with the surfaces 10.

40 The opposite end of each of the plates 17 is pivotally engaged as at 17^a with a conductor plate 22 carried by a plate 24 in connection with the high tension terminals of the coil or with the low tension terminals of the coil. The plates 22 are insulated one from the other through the medium of the insulated body 23. The pivotal connection 45 of the plates 17 and 22 permit an adjustment of the plates 17 or more particularly the roller 19 relative to the disk 8 for the purpose of spark control, as is believed to be clearly obvious to those familiar with systems of this general character.

45 The arm 18 is provided with an extension 25 with which coacts the retractile spring 26 for normally maintaining the roller 19 in contact with the surfaces 10 of the disk 8, and also operatively engaged with the extension 25 is the spark control rod 27 which is operatively engaged with the spark rod R carried by the steering column and of a well known type.

50 From the foregoing description, it is thought to be obvious that a system constructed in accordance with my invention is of an extremely simple and comparatively inexpensive nature and is particularly well adapted for use by reason of the convenience

and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

75

I claim:

1. In combination with a spark plug of an internal combustion engine and a source of energy connected with said plug, a circuit closer interposed in the connection between the spark plug and the source comprising a rotatable conductor shaft, an annular contact member surrounding the shaft and insulated therefrom, a spring arm electrically connected with the plug and contacting with the annular contact member, an insulated disk fixed to the rotatable conductor shaft and having contacts embedded therein, one of said contacts being electrically connected with the conductor shaft to afford a ground and the second contact being electrically connected with the annular contact, a pivotally supported plate adapted to coact with each of the embedded contacts of the disk, said plates being operatively connected with the electrical source and insulated one from the other, and means for maintaining said plates in contact with the periphery of the disk.

80

2. In combination with a spark plug of an internal combustion engine and a source of energy connected with said plug, a circuit closer interposed in the connection between the spark plug and the source comprising a rotatable conductor shaft, an annular contact member surrounding the shaft and insulated therefrom, a spring arm electrically connected with the plug and contacting with the annular contact member, an insulated disk fixed to the rotatable conductor shaft and having contacts embedded therein, one of said contacts being electrically connected with the conductor shaft to afford a ground and the second contact being electrically connected with the annular contact, a pivotally supported plate adapted to coact with each of the embedded contacts of the disk, said plates being operatively connected with the electrical source and insulated one from the other, means for maintaining said plates in contact with the periphery of the disk, and means for imparting movement to the plates relative to the disk for controlling the spark.

85

3. In combination with a spark plug of an internal combustion engine and a source of energy connected with said plug, a circuit closer interposed in the connection between the spark plug and the source comprising a rotatable conductor shaft, an an-

20 nular contact member surrounding the shaft and insulated therefrom, a spring arm electrically connected with the plug and contacting with the annular contact member, an insulated disk fixed to the rotatable conductor shaft and having contacts embedded therein, one of said contacts being electrically connected with the conductor shaft to afford a ground and the second contact being electrically connected with the annular contact, a pivotally supported plate adapted to coact with each of the embedded contacts of the disk, said plates being operatively connected with the electrical source and insulated one from the other, means for maintaining said plates in contact with the periphery of the disk, said conductor shaft being hollow and having the connections leading from the disk arranged interiorly thereof, and a filling within the conductor shaft.

25 4. In combination with a spark plug of an internal combustion engine and a source of energy connected with said plug, a circuit closer interposed in the connection between the spark plug and the source comprising a

rotatable conductor shaft, an annular contact member surrounding the shaft and insulated therefrom, a spring arm electrically connected with the plug and contacting with the annular contact member, an insulated disk fixed to the rotatable conductor shaft and having contacts embedded therein, one of said contacts being electrically connected with the conductor shaft to afford a ground and the second contact being electrically connected with the annular contact, a pivotally supported plate adapted to coact with each of the embedded contacts of the disk, said plates being operatively connected with the electrical source and insulated one from the other, and means for maintaining said plates in contact with the periphery of the disk.

In testimony whereof I hereunto affix my signature in the presence of two witnesses. 45

OLE HOLEN.
